VAULT

Joseph A. Patterson, Brave, Pa., assignor to The
Patterson Burial Vault Trust, Brave, Pa.

Application October 27, 1937, Serial No. 171,304

5 Claims. (Cl. 72—7)

This invention relates to burial vaults and an object of the invention is to provide a water-proof vault which when sealed will positively protect the casket from moisture.

5 Further, an object of the invention is to provide an improved concrete burial vault which will be substantially absolutely moisture-proof.

A still further object of the invention is to provide a burial vault having no metal or the 10 like exposed to the elements and consequently apt to rust to the end that the vault would be caused to deteriorate on account of rust.

Among other objects of the invention is the provision of a vault characterized by simplicity 15 and economy of construction.

The invention together with its objects and advantages will be best understood from a study of the following description taken in connection with the accompanying drawings wherein:—

20 Figure 1 is a perspective view of the vault.

Figure 2 is a longitudinal sectional view through the sealed vault.

Figure 3 is a transverse sectional view through the sealed vault.

25 Figure 4 is a fragmentary detail corner view showing the parts just prior to a sealing of the vault.

Figure 5 is a fragmentary vertical sectional view through a corner of the vault.

30 Figure 6 is a fragmentary vertical sectional view showing the vault sealed.

Referring to the drawings by reference numerals it will be seen that the improved vault 35 comprises a bottom, side and end walls, and that these walls each include an outer facing 5 of concrete, and of suitable thickness, and an inner facing 6 of concrete of slightly less thickness. Between the faces 5 and 6 is a filler 7 of water-proof material, preferably asphalt.

40 The concrete faces 5 and 6 are reinforced throughout by vertical reinforcing rods 8 and horizontal reinforcing rods 9 thus providing a strong, durable and efficient structure, it being understood in this connection that the rods 8 that extend vertically are embedded in the concrete faces 5 and 6 vertically of the vertical walls, while the reinforcing rods 9 are embedded in the concrete faces of the bottom wall.

45 Also, and as best shown in Figures 4 and 6, the inner concrete faces 6 for the side and end walls at their upper edges terminate substantially co-planar with the intermediate layer 7 of asphalt, and below the upper edges of the outer facings 5 of the vertical walls so as to pro-

vide a support for a lid indicated generally by the reference numeral 10.

The lid 10 is constructed in substantially the same manner as are the walls of the vault in that, and as clearly shown in Figure 4, the lid 10 comprises an outer concrete facing 11 reinforced as at 12, an inner concrete facing 13 reinforced as at 14, and a layer 15 of asphalt interposed between the concrete faces 11 and 13.

The inner face 13 of reinforced concrete is 10 of slightly greater dimensions than the outer reinforced concrete face 11 and the asphalt 15, and said inner face 13 is of also materially less dimensions than the vault body so that at the marginal edge portions thereof the face 13 of said 15 lid rests on the inner reinforced concrete faces 6 of the vertical walls as clearly shown in Figure 4. Thus a space 16 is left between the edges of the lid and the upper portion of the outer facings 5 for a sealing medium 18 of asphalt. When the 20 sealing medium 18 is placed in space 16 it forms a continuation of the water-proofing layer 7 and provides an effective seal for the vault.

To insure a thorough locking or binding of the sealing material 18 the outer faces 5 of the vertical walls of the vault adjacent their upper edges are provided on their inner surfaces with grooves 21, while at the upper edges thereof said faces 5 are rabbeted as at 22 and grooved as at 23 while the top face 11 of the lid 10 at its marginal edge is rabbeted as at 24 and grooved as at 25; the sealing medium being received in the grooves 21, 23, 25 and between the rabbeted edges 22 of the walls 5 and 24 of the lid face 11 as best shown in Figures 4 and 6 thereby insuring a positive seal for the vault.

30 Further in accordance with the present invention the lid 10 at spaced points in the edges of the reinforced concrete face 16 of said lid is provided with hand accommodating recesses 20 as 35 shown in Figure 4 to facilitate handling of the lid.

To provide a cushion for the lid 10 when positioned for closing the vault the inner faces 6 of the vertical walls of the vault are provided in 45 their upper edges with grooves 26 and at the extended marginal edge thereof the inner face 13 of the lid 10 is provided on its underside with a continuous groove 27 complementary to the groove 26, and accommodated within the complementary 50 grooves 26, 27 is a cushioning element 28 consisting of asphalt.

Also for guiding the lid 10 into proper seated position the inner face 13 of the lid immediately adjacent the groove 27 is provided with a con- 55

tinuous depending rib 29 that is substantially V-shaped in cross section and as clearly shown in Figure 4.

It will be understood that the outer surfaces of 5 the concrete faces 5 and the inner surfaces of the concrete faces 6 may be finished off to provide a suitable exterior finish and interior lining of a decorative character for the vault.

Also in accordance with the present invention 10 and to further assure against the accumulation of moisture within the vault the inner faces 6 of the walls of the vault for the entire bottom of the vault, and to a material point upwardly on the faces 6 of the vertical walls of the vault are 15 covered with a coating 30 having absorbing qualities, the coating 30 being preferably composed of sand, glue and cement mixed in the desired proportions and worked to the desired consistency. Such a coating, as shown at 30, and 20 described, will serve to absorb such liquid as may issue from the corpse. Thus in this manner will the bottom of the vault be maintained dry and free of moisture.

Also, interiorly of the vault, on the bottom 25 thereof, are transverse supports 31 of concrete or other suitable material for supporting the casket above the bottom of the vault.

In the manufacture of the vault, the same is cast substantially in a single operation, that is 30 to say first the concrete for the outer facings 5 of the walls of the vault are cast in a suitable mold. After the concrete for forming these faces has set and dried the mold is removed, or rather spaced relative to the set concrete when the asphalt material is then poured into the mold and 35 permitted to set for forming the water-proofing layer 7. When the water-proofing material has set and hardened the mold is further revised to provide a space for the concrete used in the setting of the concrete faces 6 and thus the concrete 40 faces 5 and 6 and the water-proof intermediate layer 7 are cast substantially as one so as to provide an integral water-proof structure. The casting of the lid is accomplished in substantially the 45 same manner, it being understood that as in the case with the vault proper first one layer then the other forming the lid 10 is cast in the same mold.

A vault embodying the features of the present 50 invention will not be likely to crack and crumble, is strong and durable, water-proof, and when sealed will serve to preserve the casket in its original state for an indefinite period of time.

It is thought that a clear understanding of the 55 construction, utility and advantages of an invention of this character will be had without a more detailed description.

Having thus described the invention what is 60 claimed as new is:—

1. A burial vault comprising a body composed 65 of inner and outer members spaced apart and a central member of waterproof material placed between the members, the outer member having its upper portion extending beyond the upper edges of the inner and center members, a lid composed 70 of inner and outer members spaced apart and a central member of waterproof material placed between said inner and outer members, the inner member of the lid being of greater length and width than the other members of the lid and of a length and width equal to the overall 75 length and width of the inner member of the body, whereby the edge portion of the inner member of the lid will rest on the upper edges of the inner member of the body when the lid is

placed on the upper portion of the body, the upper face of the lid being substantially flush with the upper edge of the outer member of the body when the lid is in place, the edges of the upper and central members of the lid forming an open 5 top chamber with the upper portions of the outer member of the body and sealing material placed in said chamber, such material contacting with the central members of the body and lid when in place.

2. A burial vault comprising a body composed 10 of inner and outer members spaced apart and a central member of waterproof material placed between the members, the outer member having its upper portion extending beyond the upper 15 edges of the inner and center members, a lid composed of inner and outer members spaced apart and a central member of waterproof material placed between said inner and outer members, the inner member of the lid being of greater 20 length and width than the other members of the lid and of a length and width equal to the overall length and width of the inner member of the body, whereby the edge portion of the inner member of the lid will rest on the upper edges of the inner 25 member of the body when the lid is placed on the upper portion of the body, the upper face of the lid being substantially flush with the upper edge of the outer member of the body when the lid is in place, the edges of the upper and central members of the lid forming an open top chamber with the upper portions of the outer member of the body and sealing material placed in said chamber, such material contacting with the central 30 members of the body and lid when in place, the inner portion of the upper edge of the outer member of the body having a recess therein and the upper portion of the edge of the outer member of the lid having a recess therein, said recesses forming side extensions for the upper part of the 35 chamber and receiving some of the sealing material.

3. A burial vault comprising a body composed 40 of inner and outer members spaced apart and a central member of waterproof material placed 45 between the members, the outer member having its upper portion extending beyond the upper edges of the inner and center members, a lid composed of inner and outer members spaced apart and a central member of waterproof material placed between said inner and outer members, the inner member of the lid being of greater 50 length and width than the other members of the lid and of a length and width equal to the overall length and width of the inner member of the body, whereby the edge portion of the inner member of the lid will rest on the upper edges of the inner member of the body when the lid is placed on the upper portion of the body, the upper face of the lid being substantially flush with the upper 55 edge of the outer member of the body when the lid is in place, the edges of the upper and central members of the lid forming an open top chamber with the upper portions of the outer member of the body and sealing material placed in said chamber, such material contacting with the central members of the body and lid when in place, the inner portion of the upper edge of the outer member of the lid having a recess therein, said recesses forming side extensions for the upper part of the chamber and receiving some of the sealing 60 material, the upper edge of the inner member of the body having a groove therein and the 65

under face of the edge portion of the inner member of the lid having a groove therein and sealing means placed in the space formed by the two grooves.

5   4. A burial vault comprising a body composed of inner and outer members spaced apart and a central member of waterproof material placed between the members, the outer member having its upper portion extending beyond the upper edges 10 of the inner and center members, a lid composed of inner and outer members spaced apart and a central member of waterproof material placed between said inner and outer members, the inner member of the lid being of greater length and 15 width than the other members of the lid and of a length and width equal to the overall length and width of the inner member of the body, whereby the edge portion of the inner member of the lid will rest on the upper edges of the inner member 20 of the body when the lid is placed on the upper portion of the body, the upper face of the lid being substantially flush with the upper edge of the outer member of the body when the lid is in place, the edges of the upper and central members of 25 the lid forming an open top chamber with the upper portion of the outer member of the body and sealing material placed in said chamber, such material contacting with the central members of the body and lid when in place, the inner portion 30 of the upper edge of the outer member of the body having a recess therein and the upper portion of the edge of the outer member of the lid having a recess therein, said recesses forming side extensions for the upper part of the chamber 35 and receiving some of the sealing material, the upper edge of the inner member of the body having a groove therein and the under face of the edge portion of the inner member of the lid having a groove therein and sealing means placed in

the space formed by the two grooves, the inner face of the upper portion of the outer member of the body having a groove therein which is in communication with the chamber and which receives some of the sealing material placed in the chamber and the under face of the edge portion of the outer member of the lid having recesses therein in communication with the chamber and forming hand holds and these recesses receiving some of the material.

5   5. A burial vault comprising a body composed of inner and outer members spaced apart and a central member of waterproof material placed between the members, the outer member having its upper portion extending beyond the upper edges 10 of the inner and center members, a lid composed of inner and outer members spaced apart and a central member of waterproof material placed between said inner and outer members, the inner member of the lid being of greater 15 length and width than the other members of the lid and of a length and width equal to the overall length and width of the inner member of the body, whereby the edge portion of the inner member of the lid will rest on the upper edges of the inner member 20 of the body when the lid is placed on the upper portion of the body, the upper face of the lid being substantially flush with the upper edge of the outer member of the body when the lid is in place, the edges of the upper and central members of 25 the lid forming an open top chamber with the upper portions of the outer member of the body and sealing material placed in said chamber, such material contacting with the central members of the body and lid when in place, 30 said inner and outer members and both the lid and the body being formed of reinforced concrete.

JOSEPH A. PATTERSON.
